DESIGN FOR A BROOCH

Vally Wieselthier, New York, N. Y., assignor to Victor Silberfeld and Jack Silberfeld, New York,
N. Y., doing business as Silson Company

Application February 1, 1938, Serial No. 74,784

Term of patent 3½ years

To all whom it may concern:

Be it known that I, Vally Wieselthier, a citizen of the United States, residing in New York city, in the county of New York and State of New York, have invented a new, original, and ornamental Design for a Brooch, of which the following is a specification, reference being had to the accompanying drawing forming part thereof.

a brooch embodying my new design; and
Fig. 2 is a front view in elevation of the brooch shown in Fig. 1.

I claim:
The ornamental design for a brooch, as shown.
